DESIGN FOR A LIGHTING FIXTURE

Albert L. Arenberg, Highland Park, Ill., assignor
to Patent License Corporation, Chicago, Ill., a
corporation of Illinois

Application March 21, 1940, Serial No. 91,124

Term of patent 14 years

To all whom it may concern:

Be it known that I, Albert L. Arenberg, a citizen of the United States, residing at Highland Park, in the county of Lake and State of Illinois, have invented a new, original, and ornamental Design for a Lighting Fixture, of which the following is a specification; reference being had to the accompanying drawing, forming a part thereof.

In the drawing:

Fig. 1 is a side elevational view of the lighting fixture, showing my new design; and

Fig. 2 is a face view of the same.

The tapered outer portion of the lighting fixture is opaque, the annular intermediate portion is translucent and the circular center portion is transparent. The essential features of my design reside in the portions shown in solid lines.

I claim:

The ornamental design for a lighting fixture, substantially as shown and described.

ALBERT L. ARENBERG.
